UNITED STATES PATENT OFFICE

137,361

DESIGN FOR A WALLPAPER OR SIMILAR ARTICLE

William Burton, Chicago, Ill., assignor to Trimz Company, Inc., Chicago, Ill., a corporation of Delaware

Application October 23, 1943, Serial No. 111,477

Term of patent 3½ years

To all whom it may concern:

Be it known that I, William Burton, a citizen of the United States, residing at Chicago, in the county of Cook and State of Illinois, have invented a new, original, and ornamental Design for a Wallpaper or Similar Article, of which the following is a specification, reference being had to the accompanying drawing forming a part thereof.

In the drawing, the figure is a plan view of a wallpaper showing my new design.

The characteristic features of my design for a wallpaper reside in the specific floral elements
and their arrangement as shown.

I claim:

The ornamental design for a wallpaper or similar article, as shown and described.

WILLIAM BURTON.
